11 Claims. (Cl. 179—7)

The present invention relates to a circuit arrangement for determining calling stations in particular in systems which are provided with forwardly operating pre-selectors.

The determination of the calling station is important for example when so-called "toll-tickets" are automatically made out in the central arrangement especially for the purpose of determining the fee, which give a permanent record of certain of the data for the connection (the number of the called station as well as the number of the calling station, time, duration of the connection and so on).

Central arrangements for determining calling subscribers' stations and transmitting signals corresponding to the individual digits of a call number are known.

The present invention relates to a central arrangement for use for a very large number of subscribers' stations in which complications are avoided as far as possible and which increases the economic working of the installation in that each junction line is associated with a number of line groups consisting of marking lines and of lines which mark the connection of different potentials and when the time occurs for determining the calling junction the marking of the latter is obtained by determination of the marking line and the amount of the potential applied and this is converted with the aid of condensers into impulses.

More specifically, the invention comprises equipment common to a large number of subscribers' lines which is adapted to be temporarily associated with each connection extended from said subscribers' lines (or with at least certain types of connections, e. g. high valued) for the purpose of determining the identity of the calling line and transmitting a code corresponding to telephone number of said calling line.

According to one feature of the invention, the identifying equipment is common to a plurality of switches accessible to all subscribers' lines over preselectors, and is adapted to be associated individually with a particular one of said switches in response to a signal received by the switch after said switch has extended the connection from the calling subscriber's line.

According to another feature, the common equipment includes a switch having a plurality of wipers with a different potential connected to each wiper. The subscribers' lines are arranged in levels in the bank of this switch, in such fashion that all lines whose telephone numbers

have, say, the same last digit appear in the same level. Whenever the common equipment is seized to identify a calling line, the switch is operated to find that line and impress upon it the potential connected to the wiper serving the level in which the calling line is arranged. The potentials connected to the different wipers of said switch vary from one another in substantially uniform steps, the highest numbered level being characterized by highest value of potential, and vice versa.

According to still another feature, the identifying equipment includes a condenser which is charged, over the connection extended from the calling line, by the potential impressed upon said line by the switch. The value of the charge placed upon the condenser depends upon the value of the potential impressed upon the calling line and hence is the same for all calling lines arranged in the same level of the switch. The condenser is then employed to control an impulse sender to transmit impulses dependent in number upon the extent to which said condenser was charged.

These and other features of the invention will be more fully understood from the following detailed description, which should be considered in connection with the drawings, and also from the appended claims.

The drawings, Figs. 1 and 2, comprise a circuit diagram embodying the invention. The two figures should be placed side by side with Fig. 1 to the left of Fig. 2. Across the top of the two figures is shown diagrammatically a connection which extends from a subscriber T_n over a junction AL, the pre-selector VW and the group selector GW.

The arrangement for marking the number of the calling subscriber and transmitting impulse trains corresponding to the individual digit number is shown briefly with "the call-number-determining arrangement" in the lower part of the figure beneath the dotted lines. Since the determination of the calling subscriber and the transmission of the impulse trains only takes up a short time such an arrangement can be used to the maximum possible extent. If in the present case it is assumed that the determination and the recording of the number of call does not occur for all connections but only for certain category, for example for high valued connections then a calling number determining device can be associated with a large number of subscribers' stations.

According to the invention it is assumed that a determining arrangement is associated with 2000 subscribers.

The main components of this arrangement are as follows:

(1) *Selectors DAW and DBW*

The selector DAW serves to mark the subscribers in the first thousands group, the selector DBW for marking those in the second thousands group. Both selectors are of the same construction, they consist of a magnet DA or DB by which 11 wipers *da1—da11* or *db1—db11* are operated. The selectors are 100 point selectors, i. e. their wipers step over contact banks consisting of 100 contact positions. The contact bank over which the wipers *da1—da10* of the selector DAW and the wipers *db1—db10* of the selector DBW step are divided into groups so that the first hundred *1H* in the first thousand *1T* or in the second thousand *2T* is marked by the first ten contacts and the second hundred *2H* by the second ten contacts and the third hundred *3H* by the third ten contacts and so on. The 1000 contact positions of each of the selectors DAW, and DBW are connected with arrangements individual to the subscribers in a definite manner so in fact contact is made with the test wiper on the pre-selector individual to a subscriber. Thus the connection of the contact positions is arranged so that the first contact of the wiper *da1* is connected with the subscriber *11* of the first hundred in the first thousand, i. e. with the subscriber whose call number ends with the digits "1111." The first contact of the wiper *da2* is connected with the subscriber "12" of the first hundred in the first thousand, i. e. with the subscriber whose call number has the last 4 digits "1112." The wipers *da3—da9* are only indicated schematically in the drawing, the wiring of their contacts to the individual subscribers following without any further consideration. The first contact of the wiper *da10* of the selector DAW is connected with the subscriber whose call number has the four last digits "1110." Similarly in the selector DBW the subscriber in the second thousands *2T* is marked. The first contact of the wiper *db1* is connected with a subscriber whose call number ends in "2111," the first contact of the wiper *db2* with a subscriber whose 4 last digits are "2112," and so on.

The second contact of the wiper *da1* is connected with the subscriber "21" of the first hundred in the first thousand, i. e. with a subscriber whose call number ends with "1121," and the second contact of wiper *da2* with a subscriber whose call number ends with "1122."

The eleventh contact of the wiper *da1* is connected with a subscriber "11" in the second hundreds in the first thousands, i. e. with a subscriber with the call number ending in "1211" while the corresponding contact of the wiper *db1* is connected with a subscriber having a call number "2211." The eleventh contacts of the wipers *da2* and *db2* are connected with subscribers having call numbers ending with "1212" and "2212" etc.

Thus the result is obtained that all the contacts over which the wipers *da2* and *db2* step are connected with subscribers whose call number has "1" as the last digit, the contacts over the wipers *da2* and *db2* with subscribers having "2" as the last digit of their call number, the contacts over which the wipers *da10* and *db10* step

have subscribers whose call numbers are terminated by the digit "0."

Further, the first, eleventh, twenty-first and so on contacts of the wipers *da1—da10* and *db1—db10* are connected with subscribers whose call numbers end with the digit "1." All the second, twelfth, twenty-second and so on contacts are connected with subscribers whose call numbers end with the digit "2."

Thus the wiring scheme of the two selectors has been described in sufficient detail.

For the purpose of marking the call number the individual wipers now have differentiating criteria. Thus the wipers *da1* and *db1* are extended to an unearthed battery of 6 volts, wipers *da2* and *db2* to one of 12 volts, the wipers *da3—da9* and *db3—db9* to one of 18-54 volts, the wipers *da10* and *db10* to one of 60 volts.

(2) *Selector DWW*

This selector consisting of the magnet DW and the wipers *dw1* to *dw4*, serves for controlling selectors DAW and DBW and for determining the call number of the calling subscriber.

(3) *Selector DMW*

This switch is operated by the magnet DM and has two wipers *dm1* and *dm2*. It serves with the aid of a storage condenser and a thermionic tube to determine the last digit of the call number and to transmit impulses corresponding to its value to the registering arrangement.

(4) *Selector DUW*

This is driven by the magnet DU and has four wipers *du1—du4*. It serves as an impulse sending control switch for transmitting impulse trains corresponding to the thousands, the hundreds and the tens digit of the call number.

(5) *Selector DEW*

Three wipers of this selector are shown which are stepped on by the magnet DE. In the setting up of high valued connections it serves to receive a signal for initiating the registering of a calling number and to connect the call number determining arrangement to the connection path.

(6) *Control switch of the magnet ST*

This switch determines the order of transmission of the impulse trains corresponding to the individual positions of the call number.

The method of operation of the arrangement shown in the drawings will now be described in detail.

When the subscriber *Tn* lifts the receiver for the purpose of setting up a high-valued connection, then in known manner the pre-selector VW is started up and seizes a free group selector. The feeding of the calling subscriber follows in known manner over the feeding bridge relays A and B in the selector: potential, winding of relay A, wiper *a* of the pre-selector VW, upper conductor of the junction line, subscriber's loop, lower conductor of the junction line, wiper *b* of the pre-selector VW, winding of the relay B, potential. Over the test wiper *c* of the pre-selector the following circuit is completed: earth, battery, contacts not shown, winding of relay T, wiper *c* of the pre-selector, winding of relay C in the group selector GW, contact *42kk* (mechanical contact opened as long as the group selector is off-normal), earth. In addition to relay T in the pre-selector whose function is not of importance

here and therefore is not described, relay C in the group selector operates and closes its contact 41c. Operation of relay Ab over its winding II does, however, not take place since the relay is short-circuited by earth over contact 41c.

By transmitting impulse trains the subscriber now sets up the connection in known manner. In the group selector relay Q is connected up over lower talking conductor, choke Dr1 and contact 44ab. This relay serves to receive the signal for initiating registration of the call number of the calling subscriber. If, for example, after the setting up of one or more switching stages, a particular position is reached e. g. the position with which a registering arrangement is associated (printing or punching device) then from this position battery potential is connected to the lower talking conductor. The operation of relay Q effects the connection of the call number determining arrangement so that in the embodiment the registering of the call number is brought about during the setting up of the connection. It is understood that the registering of the call number can also be undertaken at a different moment, e. g. the termination of a connection. Instead of the connection of relay Q the signal for initiating the registering can be performed in a different manner for example in dependence on the position of the group selector, on the assumption, of course, that the position of the group selector has already been arranged to differentiate between the values of the connections. In this case then, relay Q is removed and contact 40q which starts the call number determining arrangement, is replaced by means of a bank contact which is closed by the positioning of the group selector corresponding to a high valued connection.

When contact 40q is closed and the call number determining arrangement is free the following circuit is completed: earth, contacts 40q, 39ab, resistance Wi16, winding of relay An, battery, earth. In this circuit relay An is operated and by closing its contact 30an completes the following circuit for relay R: earth, contacts 30an, 31v, winding of relay R, resistance Wi14, battery, earth. At contact 21r the magnet DE of the selector DEW is energised so that the wipers de1 to de3 are stepped on to the next contact. The magnet DE has a contact 32de which is now closed so that the relay R is restored by means of the short circuit and thus the contact 21r is opened. After the release of contact 32de relay R is again energised and at contact 21r again energises magnet DE. In this manner the wipers of the selector DEW are stepped on until by means of a wiper de2 the group selector is reached in which the relay Q is operated. The following circuit is then completed: earth, contacts 40q, 39ab, 38ab, winding I of relay Ab, wiper de2, contacts 36e, 33r, windings I and II of relay P, battery, earth. In this circuit relay P operates and (in the group selector) relay Ab. Relay P closes its contact 34p and thus completes a holding circuit for itself over its winding II. Relay Ab closes contact 37ab (make-before-break contact) so that for the duration of the registering of the call number the following circuit remains closed: earth, resistance Wi15, contact 37ab, winding I of relay Ab, wiper de2, contacts 36e, 34p, winding II of relay P, battery, earth. Relay Ab also opens its contact 39ab and thus removes the starting earth from relay An. By the opening of contact 30an further operation of relay R and thus further operation of the magnet DE by means of

the contact 21r is prevented. The selector DEW thus remains in the position over which it has found the group selector GW.

After the opening of mechanical contact 42kk 5 the earth potential is maintained on the c-conductor over contacts 41c and 43ab. After the opening of contact 43ab earth potential is connected over contact 41c and winding II of relay Ab. Relay Ab remains energised in this circuit 10 for the duration of the connection.

By the closing of contact 29p relay V is energised slowly due to the resistance connected in parallel with its winding and at contact 31v a further point is opened in the circuit for relay 15 R. Before the operation of relay V the following circuit is completed for both magnets DA and DB of the selector DAW and DBW: earth, contact 3v, 2p, magnets DA and DB, battery, earth. The wipers da1—da11 and db1—db11 are 20 thus stepped on to the next contact. The magnet DA has a contact 4da which in operating energises relay K. By means of contact 5k the following circuit is completed: earth, contact 5k, wiper dw3 in the rest position, winding of relay 25 A2, battery, earth. Relay A2 closes contact 14a2 and thus the following circuit: earth, battery, magnet DW of the selector DWW, contacts 12um, 14a2, winding I of relay U, contact 13u, earth. The magnet DW steps the wipers dw1 to dw4 on 30 to contact 1, and wiper da1 is connected up over wiper dw1. It is now determined by wiper dw1 whether the wiper da1 rests on the contact which is connected with wiper c of the preselector of the calling subscriber. Assume that this is not 35 the case. Then after the operation of relay U in the above-mentioned circuit the contacts 13u, 15u, 21u, 19u and 24u are opened and the contacts 20u and 18u closed. Contact 17u is only opened when relay U operates over both windings, i. e. when contact 13u is opened. Thus the 40 result is obtained that contact 17u is only operated after the closing of contacts 18u and 20u. By means of the latter contacts the storage condenser C1 is connected to earth and to the grid of the thermionic valve. Since the condenser C1 has no charge no switching is brought about by 45 the operation of this contact.

The thermionic valve RE1 is arranged so that when battery potential is applied to the grid over contact 17u and resistance Wi12, relay H in the anode circuit cannot operate. If, however, there is no battery potential applied relay H operates. Since in this case the storage condenser C1 is to be without charge relay H is energised after the 50 opening of contact 17u. It opens its contact 6h and thus the circuit for relay A2 for which after the stepping of the switch from its normal position the following circuit is completed: earth, battery, winding of relay A2, wiper dw3 on the 55 contact segment, contact 6h, earth. After the release of relay A2 after the opening of contact 6h the circuit for the magnet DW of the selector DWW and for relay U is interrupted, at contact 14a2. On its release relay U again connects battery potential at contact 11u to the grid of the 60 thermionic valve RE1 whereby the release of relay H is effected. At contact 6h relay A2 is again energised and over contact 14a2 the magnet DW (its wipers therefore reach the second 65 contact) and relay U are energised. The storage condenser C1 is again connected to the grid of the valve RE1 while battery potential over resistance Wi12 is disconnected from the grid of the valve. 70

In this manner the wipers dw1—dw4 are

stepped on over their contact banks. Thus the wiper *dw1* tests, on stepping over the first 10 contacts, whether one of the wipers *da1*—*da10* rests on the contact to which the calling subscriber is connected and, on stepping over the contacts 11 to 20, whether one of the wipers *db1*—*db10* rests on the contact to which the calling subscriber is connected. When the wipers of the selector DWW reach the last contact 25 then over the wiper *dw2* in position 25 both magnets DA and DB of the two selectors are energised. The wipers of these two selectors are then stepped on to the next contact. At contact 4*da* relay K is again energised and at contact 5*k* relay A2 energises, which by closing contact 14*a2* effects the second rotation of the selector DWW. By means of the wiper *dw1* it is now determined whether one of the wipers *da1*—*da10* and *db1*—*db10* is connected to the calling subscriber and which of these contacts it is.

Assume that the last four digits of the number of the calling subscriber are the digits "1161." The wiper *c* of the preselector of the calling subscriber *Tn* is thus extended to the sixth contact of the contact bank associated with wiper *da1*. After the wipers of the selectors DAW and DBW are connected to the sixth contact the selector DWW begins its rotation and reaches contact 1 so that the storage condenser C1 receives a charge by means of the battery potential of 6 volts connected to the wiper *da1*. The charging circuit for the condenser C1 is as follows: battery potential of 6 volts, wiper *da1*, contact 6, marking line "61," wiper *c* of the preselector, wiper *de1* of the selector DEW, contacts 35*p*, 24*u*, 19*u*, condenser C1, contacts 21*u*, 15*u*, wiper *dw1*, contact 1, battery potential of 6 volts. In parallel with the condenser C1 a further storage condenser C2 is connected over contacts 22*um* and 25*um*. This condenser in addition to the condenser C1 is charged by means of the battery potential of 6 volts on the wiper *da1*. The charging period is determined by the delay with which the relay U operates after the closing of contact 14*a2* (brought about by the short circuit of winding II at contact 13*u*). The connection of the charged condenser C1 to the grid of the thermionic valve RE1 is effective so that after the opening of contact 17*u* and disconnection of the battery potential connected over the resistance *Wi12* the relay H in the anode connection remains in the normal position. Thus the relay A2 is maintained energised for some time over: earth, battery, winding of relay A2, wiper *dw3* in the operated position, contact 6*h*, earth and the selector DWW remains at rest.

After the setting of the selector DEW and on the operation of relay P, at contact 8*p* the following circuit is completed for relay U1: earth, battery, resistance *Wi18*, contact 8*p*, resistance *Wi13*, winding of relay U1, earth. As previously mentioned relay A2 is operated intermittently and thus the stepping on of the selector DWW is effected. By means of contact 1*a2* a circuit is completed for short-circuiting relay U1. The short operating period of relay A2 during the stepping of the selector DWW is not sufficient however to restore relay U. When after the testing of the calling subscriber by means of the selector DWW, relay A2 remains energised for some time, then contact 1*a2* also remains closed for some time and the release of relay U1 is brought about. The following circuit is then completed: earth, battery, resistance *Wi18*, contacts 8*p*, 11*a2*, 10*u1*, winding of relay *Um*, earth.

In this circuit relay *Um* operates and closes the following holding circuit for itself: earth, battery, resistance *Wi18*, contacts 8*p*, 9*um*, winding of relay *Um*, earth. Relay *Um* by opening contact 16*um* disconnects relay H. By the opening of contact 12*um* the circuit for the magnet DW and relay U is interrupted. By the closing of contacts 26*um* and 23*um* the storage condenser C2 charged with 6 volts is connected on one hand to the wiper *dm1* of the selector DMW and on the other hand to the grid of the valve RE2.

There follows in the first place a determination of the thousand digit and transmission of corresponding impulses over the lower talking conductor to a succeeding registering arrangement (printing or punching device). By the closing of contact 65*um* the following circuit is completed: earth, control switch contact 66*st* (closed in positions 1 to 3 of the control switch), wiper *du4* in the rest position, contacts 65*um*, 64*h3*, 62*e*, 61*b1*, winding of relay A1, battery, earth. In this circuit relay A1 operates and its operation is delayed since parallel to its winding over contact 60*k1* a damping resistance *Wi16* is connected. By the closing of contact 47*a1* the first impulse transmitted over the lower line to the registering device as follows: earth, contacts 46*k1*, 47*a1*, 48*um*, wiper *de3*, contact 45*ab*, choke *Drl*, lower talking conductor, wiper *b* of the group selectors and further to the registering arrangement in a subsequent connecting stage. By the closing of contact 51*a1* the following circuit is completed for relay V1: earth, contacts, 50*h2*, 51*a1*, winding of relay V1, battery, earth. Relay V1 operates in this circuit and at contact 52*v1* energises the relay W1. By the closing of contact 58*a1*, relay B1 is energised slowly since parallel to its winding over contact 59*k1* a damping resistance 40 *Wi17* is connected. By the opening of contact 61*b1* the circuit for relay A1 is interrupted so that by the opening of contact 58*a1* the circuit for relay B1 is interrupted. At contact 61*b1* the circuit for relay A1 is again completed. Relays A1 and B1 therefore form an interrupting arrangement which by means of contact 47*a1* transmits impulses over the lower talking conductor to the registering arrangement and simultaneously by means of contact 56*b1* the relay B1 transmits impulses to the magnet DU over: earth, contact 56*b1*, control switch contact 58*st* (closed in positions 1—3), magnet DU, battery, earth.

The wiper *dw1* over contact 1 and wiper *da1* has found the calling subscriber. The wiper *dw4* thus rests on contact segment 1—10. If the wipers of the sender control switch DUW reach the first contact after the first operation of magnet DU by means of contact 56*b1* then the following circuit is completed: earth, wiper *dw4*, contact segment 1—10, wiper *du1* on contact 1, control switch contact 75*st* (closed in the control switch position 1), winding of relay H2, battery, earth. In this circuit relay H2 operates and by closing its contact 49*h2* energises relay K1 over the winding 1. Relay K1 opens its contact 46*k1* and thus prevents the further transmission of impulses by means of contact 47*a1* over the lower talking conductor. Relay K1 also closes a holding circuit for itself over contact 53*k1* as follows: earth, contacts 52*v1*, 53*k1*, winding II of relay K1, windings I and II of relay H3, battery, earth. The interrupting action between relays A1 and B1 is continued until the wiper *du4* has stepped over its segment and reached the normal position again. When the wiper *du1* has left contact 1

relay H2 is restored. Contact 50h2 is closed and the circuit for relay V1 is further maintained. This relay, due to its slow release, has not during the short opening of contact 50h2 the opportunity of restoring. During the short interruptions at contact 51a1 during the interaction between the relays A1 and B1, relay V1 cannot restore. Relay H3 closes its contact 55h3 and short circuits its winding II whereby the release of the relay is delayed. By the opening of contacts 59k1 and 60k1 the slow to release feature for relays A1 and B1 is removed so that their interaction is carried on more rapidly during the time in which impulses are not transmitted over the lower talking conductor and the selector DU is rapidly restored to normal.

When wiper du4 has reached its normal position the circuit for relay A1 is interrupted for some time (contact 64h3 open). Due to the long opening of contact 51a1 relay V1 has the opportunity of restoring. On the opening of contact 52v1 relays W1, K1 and H3 restore. During the release period for relay H3, the following circuit is completed for relay X: earth control switch contact 66ST (closed in the position 1-3), wiper du4 in the rest position, contacts 65um, 63h3, 69w1, winding of relay X, resistance Wi, battery, earth. At contact 70x, relay X locks up. By the closing of contact 68x the control switch magnet ST is energised and the control switch is then brought to position 2. By the closing of contact 71st relay X is restored by the short circuit and thus opens contact 70x. Meanwhile relay H3 has restored and closed contact 64h3. There follows the further connection of the impulse relay A1 over the following path: earth, control switch contact 66st (closed in positions 1-3), wiper du4 in the normal position, contacts 65um, 64h3, 62e, 61b1, winding of relay A1, battery, earth. At contact 58a1 the relay B1 is again connected and the interaction of the two relays begins again. When wiper du4 moves off-normal the circuit for relay A1 extends over the contact segment short circuiting contacts 65um and 64h3. The relays A1 and B1 bring about a further operation of the selector DUW. By the closing of contacts 59k1 and 60k1 both relays are rendered slow-to-release so that the impulse transmission of the registering arrangement continues over the talking conductors at the required speed.

In this operation of the selector DUW impulses are transmitted in accordance with the hundreds digit of the call number. The hundreds digit is transmitted by the position of the wipers of the selectors DAW and DBW. When these wipers rest on contacts 1 to 10 the signal transmitted indicated that that call number is in the first hundred. When the wipers rest on the contacts 11-20 the signal indicates that the number of the calling subscriber is in the second hundred and so on. Since the position of the two selectors DAW and DBW is the same it is sufficient to mark the hundreds digit over one wiper of one of the two selectors. In the embodiment this is performed by the wiper d41 of the selector DAW. Since the calling subscriber is assumed to lie in the first hundred the wiper d41 of the selector DAW rests on contact segments 1-10. When under the action of the relay interrupter the wipers d41-d44 of the sender control switch DUW are in the first position, and by the closing of contact 47a1 an impulse is transmitted over the lower talking conductor, to the registering arrangement and consequently the following circuit is completed: earth, wiper d41, contact seg-

ment 1-10, wiper du2 on contact 1, control switch contact 76st (closed in the control switch position 2), winding of relay H2, battery, earth. Relay H2 operates in this circuit and at contact 5 49h2 energises relay K1 which by the opening of contact 46k1 prevents any further impulse transmission to the registering arrangement. Operations now occur which are necessary for the transmission of impulses for the tens digit. If the selector DU has completed its operation then in the manner described, by means of relay X the control switch is brought to position 3. Thus over the control switch contact 77st the wiper du3 of the sender control switch DUW is connected which now serves to determine the tens digit of the wiper.

The tens digit of the call number is determined by the position of the wipers of the selectors DAW and DBW within the individual contact groups for marking the hundreds digit. The contact bank of the wiper db11 of the selector DBW is so arranged that all contacts with the first digit "1" are connected together (i. e. contacts 1, 11, 21, and so on) and are extended to contact 1 of the contact bank stepped over by the wiper du3. A1 contacts with the units digit "2" (i. e. contacts 2, 12, 22, etc.) are extended to the contact 2 of the contact bank of the wiper du3 and so on.

In the present embodiment, the wipers of the selector DAW and DBW are stopped on the sixth contact of the first hundred. Contact db11 thus rests on contact 6, and is connected to contact 6 of the contact bank of the wiper du3. On the next operation of the selector DUW by means of contact 47a1 these impulses are transmitted over the lower talking conductor to the succeeding registering arrangement. When this has taken place the following circuit is completed for relay H2: earth, wiper db11 on contact 6, wiper du3 on contact 6, control switch contact 77st (closed in position 3), winding of relay H2, battery, earth. Relay H2 with the aid of relay K1 terminates the transmission of further impulses to the registering arrangement. When the sender control switch DUW has completed its rotation, then in the manner described, by means of relay X the stepping on of the control switch to the next position (i. e. position 4) takes place. After the release of relay H3 in the manner described the following circuit is completed: earth, control switch contact 67st (closed in position 4 of the control switch), wiper dm2 in the normal position, wiper du4 in the normal position, contacts 65um, 64h3, 62e, 61b1, winding of relay A1, battery, earth. The interaction of the two relays A1 and B1 begins again. The selector DUW is now no longer controlled by contact 56b1 but the selector DMW instead whose magnet DM receives impulses over the following path: earth, contact 56b1, control switch contact 57st (closed in position 4 of the control switch), magnet DM, battery, earth. After the stepping on of the wiper dm1 to the normal position the circuit for relay A1 extends over the contact segment of wiper dm2, contacts 62e and 61b1 short circuiting the wiper du4 and contacts 65um and 64h3. The selector DMW makes one complete rotation.

The wiper dm1 steps over 10 contacts which are connected with the individual potential stages of a potential divider constructed of resistances Wi1-Wi10. As mentioned previously over contact 23um wiper dm1 is connected with the storage condenser C2 which is charged by the potential of 6 volts applied to the valve while over contact 26um the condenser is extended to the grid

of the thermionic valve RE2. The condenser C2 acts as battery potential of 6 volts. Therefore over wiper *dm1* in the zero position there is connected to the grid of the valve RE2 a potential of $60+6=66$ volts compared with 60 volts of the cathode of the valve, i. e. the bias compared with the cathode is 6 volts negative. This negative bias on the grid cuts off the anode current so that relay H1 which is connected with earth over contact 28um cannot operate. If the wiper *dm1* had reached the first contact after the first operation of magnet DM by means of contact 56b1 which contact is connected to a potential of 54 volts then a potential of $54+6=60$ volts is connected to the grid of the valve, i. e. the grid potential no longer exceeds the cathode voltage which is 60 volts. Relay H1 thus operates, since the grid no longer cut off anode current. By means of contact 47a1 an impulse is transmitted over the lower talking conductor to the registering arrangement. Relay H1 closes its contact 54h1 and thus over contact 52v1 and earth a circuit is completed for relays K1 and H3. Relay K1 by opening its contact 46k1 prevents further impulse transmission to the registering device. The further stepping on of the wipers of the selector DMW is thus without effect on the registering arrangement. If the wipers of the selector DMW have reached their normal position the following circuit is completed for relay X: earth, control switch 67st (closed in position 4 of the control switch), wipers *dm2* and *du4* in the normal position, contacts 65um, 63h3, 69w1, winding of relay X, resistance *Wi*, battery, earth. By the closing of contact 68x the control switch is stepped on to position 5. The following circuit is completed: earth, control switch contact 72st (closed in position 5 of the control switch), winding of the relay E, battery, earth. Relay E locks up in the following circuit: earth, contacts 74v, 73e, winding of relay E, battery, earth.

Relay E brings about the release of the arrangement shown. By the opening of contact 36e relay P is restored. This opens the circuit for relay V at contact 29p. By the closing of contact 31v relay R is connected to the contact 30an so that when the contact corresponding to contact 40g of another connecting stage is closed after the completion of the circuit at the closing of contact 30an, the selector DEW is set on the new connecting stage. By the opening of contact 8p the holding circuit for relay Um is interrupted so that over contact 12um the magnet DW and the relay U operate, and by the opening of contact 17u, relay H connected by contact 16um in the anode of the thermionic valve is operated. By the opening of contact 6h relay A2 is restored and relay U is disconnected at contact 14a2. By the closing of contact 17u relay H is again disconnected and relay A2 connected. In this way the magnet DW of the switch DWW receives impulse until its wipers have been restored to normal.

If the storage condenser is charged with another value, for example 18 volts connected over the wiper *da3* to *db3* the wiper *dm1* must execute three steps, i. e. it must be set on the potential stage of 42 volts until the anode current is no longer shut off by the grid. Thus in this case in order to mark the units digit of the call number 3 impulses are transmitted over the lower talking conductors to the registering device.

I claim:

1. In a telephone or like system, groups of subscribers' lines, identifying equipment com-

mon to said lines, means in said equipment for producing electrical potentials of different values, each value corresponding to a different one of said groups of lines, means operated to extend a connection from any calling one of said lines, means in said equipment then operated to find said calling line and to impress upon it a particular potential of a value corresponding to the group of which said calling line is one, and means controlled, over the connection extended from the calling line, by the potential impressed upon said calling line to transmit a variable impulse code depending upon the value of said potential.

2. In a telephone or like system, a plurality of groups of lines, identifying equipment common to said lines, means in said equipment for producing electrical potentials of different values, each value corresponding to a different one of said groups of lines, means common to said lines operated to extend a connection over any one of said lines, means operated after said connection has been extended for then associating said identifying equipment individually with said one line, and means in said equipment controlled by said last means to impress upon said one line a particular potential of the value corresponding to the group of which said line is one.

3. In a telephone or like system, a plurality of subscribers' lines, means for extending a call from any one of said lines, means common to said lines for identifying the calling line, said last means including a switch having said lines arranged in levels in its contact bank, means for operating said switch to find the calling line and to impress upon said line a potential depending in value upon the contact bank level in which said line is found, and means controlled by the value of said potential impressed upon said line to transmit an impulse code corresponding to the level in which said calling line is found.

4. In a telephone or like system, a plurality of subscribers' lines, a plurality of switches common to said lines, means for extending a connection from any calling one of said lines to any one of said switches, means then effective to apply a different potential to each of said subscribers' lines at the same time, discriminating means associated with said one switch and controlled over the connection extended thereto from said calling line by the particular one of said potentials applied to said calling line, and means controlled by said discriminating means for transmitting an impulse code indicative of said potential applied to said calling line.

5. In a telephone or like system, two lines, means common to said lines for extending calls over either of said lines, means for characterizing one of said lines by a potential of one value if a call is extended over that line and for characterizing the other of said lines by a potential of a different value if a call is extended over said other line, and means common to said lines effective after said first means has extended a call over either of said lines to determine the identity of the line over which said call is extended from the value of the potential characterizing that line.

6. In a telephone or like system, a plurality of lines each having a potential of a different value associated therewith, means for extending calls over any of said lines, and means common to said lines controlled by the extending of a call over one of said lines to transmit a variable impulse code dependent upon the value of said potential associated with said one line, thereby

to identify the line over which said call was extended.

7. In a telephone or like system, a plurality of lines, a different source of potential associated with each of said lines, a condenser common to said lines, means for extending calls over any of said lines, means operated to charge said condenser from the source associated with a particular line when a call is extended over that line, said condenser charged differently from the different sources and thereby effective to register the identity of the line over which the call is extended.

8. In a telephone or like system, a plurality of subscribers' stations, a condenser common to said stations, means for extending a call from any of said stations, means common to said stations operated to determine which of said stations is the calling station, and means controlled by said last means to charge said condenser to a variable potential depending upon which station is the calling station.

9. In a telephone or like system, a plurality

of lines, a condenser common to said lines, means for extending a call over any of said lines, means common to said lines operated to determine which of said lines said call is extended over, and means controlled by said last means to charge said condenser to a value depending upon which of said lines said call is extended over.

5 10. In a telephone or like system, a plurality of lines, a condenser common to said lines, means for extending a call over any of said lines, and means operated after said call has been extended to place upon said condenser a charge automatically depending in value upon which line said call was extended over.

15 11. In combination, a plurality of lines, a condenser common to said lines, means for marking any of said lines to distinguish that line from the other lines, means then operated to determine which of the lines is marked, and means controlled by said last means for charging said condenser to a value depending upon which line is marked.

GEORG ZAPF.
